UNITED STATES PATENT OFFICE.

JAMES W. McELROY, OF PHILADELPHIA, PENNSYLVANIA.

DESIGN FOR A DOORSTOP.

Application filed March 27, 1923. Serial No. 5,611. Term of patent 7 years.

To all whom it may concern:

Be it known that I, JAMES W. McELROY, a citizen of the United States, residing at Philadelphia, in the county of Philadelphia and State of Pennsylvania, and whose post-office address is 510 North Marshall Street, Philadelphia, Pa., have invented a new, original, and ornamental Design for a Doorstop, of which the following is a specification, reference being had to the accompanying drawing, forming a part hereof.

The figure is a perspective view of a doorstop, showing my new design.

I claim:

The ornamental design for a doorstop, as shown.

JAMES W. McELROY.
